United States Patent Office.

JACOB A. SHERMAN, OF NEW YORK, N. Y.

Letters Patent No. 74,158, dated February 4, 1868; antedated January 24, 1868.

IMPROVEMENT IN TRUSSES.

The Schedule referred to in these Letters Patent and making part of the same.

TO ALL WHOM IT MAY CONCERN:

Be it known that I, JACOB A. SHERMAN, of the city and State of New York, have invented, made, and applied to use a certain new and useful Improvement in Trusses for Hernia; and I do hereby declare the following to be a full, clear, and exact description of the said invention, reference being had to the annexed drawing, making part of this specification, wherein—

Figure 1 is a plan of said truss, and

Figure 2 is an elevation of the same.

Similar marks of reference denote the same parts.

The object of this invention is to apply an inward and upward pressure to a hernia from a light and portable instrument, that is easily strapped to the person, and will yield freely to the motion of the body.

The nature of the said invention consists in a compound curved pad-spring applied to a bar extending across the person, and carrying a second spring, that acts in aid of the first spring, and is adjusted in its pressure by a movable finger applied on the bar. By this construction the yielding support of the pad causes an inward and upward pressure upon the hernia, of the character often required for the relief or cure of the same.

In the drawing, *a* is a metal bar, to one end of which the strap *b* (only partially shown) is applied, and *c* is the button over which the other end of the strap passes. I prefer this mode of attaching the bar *a*, although the same might be extended and receive a back-pad or pads, to take the place of the strap *b*. *d* is the truss-pad spring, formed with a compound curvature, the same curving inwardly and twisted spirally, as seen in fig. 1, and attached at one end to the bar *a*. At the end of this spring *d* is the truss-pad *e*, of any desired character. The same is attached by the screws *i* and *o*, the latter passing through a segmental slot, to allow of adjusting the pad. *f* is a second spring, attached at one end to the bar *a*, and at the other end provided with a joint and loop, *g*, taking around the spring *d*, and connecting the two, but allowing the end of *f* to slide on *d* as the two springs are compressed. The finger *h* projects from a clip, *k*, around the bar *a*, and can be moved along on the same, to regulate the action of the spring *f* and its effective pressure in aid of the hernial pad-spring *d*.

This truss may be made for either side of the person, or both.

What I claim, and desire to secure by Letters Patent, is—

The curved spring *d*, carrying the hernial pad, in combination with the bar *a* and spring *f*, substantially as and for the purposes set forth.

I also claim the sliding finger *h*, fitted and acting substantially as specified.

In witness whereof, I have hereunto set my signature, this eighth day of February, A. D. 1867.

J. A. SHERMAN.
